US0D1066940S

(12) **United States Design Patent** (10) **Patent No.:** **US D1,066,940 S**
(45) **Date of Patent:** **** Mar. 18, 2025**

(54) **CIRCULAR MODULAR FLORAL ARCH**

(71) Applicant: **Syndicate Sales, Inc.**, Kokomo, IN (US)

(72) Inventor: **Trent A. Harshman**, Galveston, IN (US)

(73) Assignee: **Syndicate Sales, Inc.**, Kokomo, IN (US)

(**) Term: **15 Years**

(21) Appl. No.: **29/870,877**

(22) Filed: **Feb. 7, 2023**

(51) **LOC (15) Cl.** **08-99**

(52) **U.S. Cl.**

USPC **D25/100**

(58) **Field of Classification Search**

CLAIM

The ornamental design for a circular modular floral arch, as shown and described.

DESCRIPTION

FIG. 1 is a front right perspective view of the circular modular floral arch incorporating our new design;
FIG. 2 is a back left perspective thereof;
FIG. 3 is a rear view thereof;
FIG. 4 is a front view thereof;

(Continued)

FIG. 5 is a top view thercof;
 FIG. 6 is a bottom view thercof;
 FIG. 7 is a left view thereof; and,
 FIG. 8 is a right view thereof.

1 Claim, 6 Drawing Sheets
